ACOUSTICAL CEILING CONSTRUCTION

James S. Offutt and Carl S. Strom, Chicago, Ill.

Application November 12, 1931, Serial No. 574,524

9 Claims. (Cl. 189—88)

This invention relates to building constructions, and has reference more particularly to building constructions for acoustical purposes in preventing the reflection of sound from a ceiling.

5 In the construction of acoustical ceilings of the type employing a perforated metal membrane backed by sound absorbing layers, some difficulty has been experienced in erecting the ceiling due to high labor cost resulting from faulty attachment of the perforated membranes. It has heretofore been difficult to maintain the lower faces of the membrane in a single plane, with the result that uneven light reflection from the membrane caused the lower surface of the ceiling to 10 have objectionable high lights and poor appearance. The acoustical ceilings heretofore proposed commonly placed the sound absorbing fibrous material directly upon the membrane, with the result that when the membranes were 15 washed, some of the washing liquid would soak into the fibrous mat and then drip downwardly to again soil and deface the bottom surface of the membrane.

An object of this invention, therefore, is to provide an acoustical ceiling construction in which an improved attaching means is used, which reduces the labor of erection to a minimum.

Another object of the invention is to provide an acoustical ceiling construction in which the 30 bottom faces of the perforated membranes lie in a single plane so that light reflection is uniform from all the membranes.

A further object of the invention is to provide a quickly erected acoustical building construction 35 in which the fibrous absorbing layer is separated a substantial distance from the membrane to permit the lower surface of the membrane to be washed effectively; also to improve building constructions in other respects hereinafter specified and claimed.

Reference is to be had to the accompanying drawings forming a part of this specification, in which

Fig. 1 is a perspective view of one of our improved perforated metal membranes,

Fig. 2 is a perspective, fragmentary view of our acoustical ceiling, showing the method of attachment to the ceiling,

Fig. 3 is a fragmentary, sectional elevation 50 through the acoustical ceiling construction,

Fig. 4 is a fragmentary, perspective view of a modified form of acoustical ceiling construction,

Fig. 5 is a fragmentary, perspective view of a further modified form of ceiling construction, 55 and

Fig. 6 is a perspective view of a still further modified form of ceiling construction.

Our improved acoustical ceiling is characterized in that it can be easily installed in either old or new buildings. The ceiling proper 10 may consist of metal lath and plaster, plasterboard or any other type of ceiling desired. The ceiling 10 is supported in the usual fashion from joists not shown, and is supported around its edges by walls 11 which may also be of any desired construction. Flexible H shaped rails 12 or other suitable support bars or runner means are suspended a substantial distance below the ceiling 10 by means of quick gripping clamping brackets 13 or any other suitable means. The brackets 13 are preferably non-continuous and are preferably formed of a piece of strap, cold rolled steel composed of two integral legs 14 L-shaped in contour and having U shaped clamps 15 formed on the bottom end of each leg for engaging upper rail 10 flanges 16 which are formed on a web 17 of the rails 12. An outstanding horizontal flange formed on the clamping bracket 13 may be secured by expansion or toggle bolts 17 to the ceiling 10.

In order to cause the clamps 15 to tightly grip the flanges 16, a connecting bar or rod 18 preferably spans the distance between adjacent rails 12, said bar 18 being preferably provided on each end with a U shaped return bent clamp 19, which 30 is arranged to embrace the downwardly extending clamping legs 14. A U shaped catch 20 is formed on the outer leg 21 of the clamp 19. When installing, the legs of the clamp 19 spread slightly to grip the clamp leg 14 until catch 20 snaps over 35 the forward edge of one of the clamp legs 14. An integral lug 22 is struck outwardly from one of the legs 14, so as to engage the top edge of clamp leg 21 and prevent said clamp leg from being inadvertently raised out of clamping position after 40 erection.

A pad of light weight material 23, preferably of a fibrous nature, such as mineral wool, hair felt or vegetable fiber, is supported by the means 18. The pads 23 are preferably of a width substantially equal to the distance between the rails 17 and of a length preferably about two to five times the width of the pads. The pad 23 is the active sound absorbing material on whose absorption the acoustical properties of our improved ceiling largely depend. In order to prevent the pad 23 from sagging between the bars 18, support bars or the like 24 are placed intermediate bars 18 and are provided at each end with a return bent hook 25 which engages with one of the 55

rail flanges 16. The support bars 24 also serve to space apart the rails 12 at a uniform distance corresponding to the width of the perforated membrane to be hereinafter described.

5 In order to present a washable surface of pleasing architectural appearance below the sound absorbing pad 23, we provide a metal membrane 27 in which are formed perforations 28. These perforations may be triangular in shape as shown, 10 or may be any other desired shape, such as round or slotted, to harmonize with the finish used in any room to be equipped with the acoustical ceiling. The membrane 27 is preferably formed of a light weight, tin-plated, non-tempered iron, or 15 aluminum, but any suitable metal or non-metal may be used if desired. It is important that the membrane 27 be perfectly flat, so that when paint or other decorative surface is applied to the lower face of the membrane, no high lights or objectionable markings will be seen by people occupying the room containing the acoustical ceiling. The membrane 27 may be square or rectangular in shape, or, in fact, any other desired shape, and the edges thereof are turned upwardly 20 at an angle to form bevel 29, and are then bent vertically upward to form vertical flanges 30 which abut one against the other at the edges of adjoining membranes to accurately align said membranes. The membranes 27 with their upward turned edges are preferably formed accurately by means of dies so that the distance between the top of the flanges 30 and the bottom face of the membranes is exactly uniform on all of the membranes. The top edges of the flanges 30 25 preferably abut against bottom flanges 31 formed on the rails 12.

In order to support the membrane 27 with the upper edges of flanges 30 tightly abutting against the rail flanges 31, we provide a plurality of spring clips 32 which are preferably 30 tempered metal, which curve downwardly toward the upper face of the membrane 27 to form a shoulder 33, which is preferably spot welded to the inner face of the membrane 27. Inside of the shoulder 33, the spring clip 32 has an upwardly 35 extending loop 34, which again extends downward to form a clip end 35 which engages against the upper face of the membrane 27. The attaching or outer end of the clip 32 preferably extends slightly downwardly to form a shoulder 36 which contacts with the upper face of rail flanges 31 with a substantially single line contact, and said clip then is formed upwardly to form a flange 37. Triangular holes 28a are also preferably 40 formed in the spring clip 32 adjacent the shoulder 33 so that said openings 28a register with corresponding openings in the membrane 27, thus making the clips invisible from the bottom face of said membrane.

45 It will be seen that the spring clips 32 have a tendency to lift the weight of the center of the membrane 27 adjacent shoulder 33 and thus counteract the weight of the membrane and prevent it sagging down out of an exact plane surface as it otherwise has a tendency to do under its own weight. Owing to the fact that the membranes 27 are resiliently supported by spring clips 32 on the rail flanges 31, said membranes are free to vibrate in their center area under the impact of the sound 50 wave and thus absorb some of the energy of the impinging sound waves and increase the overall sound absorbing efficiency of the ceiling construction. It will also be noted that a considerable clearance is allowed between the upturned flanges 55 55 37 on the spring clips and the web 17 of the rails

so that exact spacing of the rails is not necessary and the cost of erection is, therefore, considerably reduced. In the construction described a considerable space 38 is provided between the membrane 27 and pad 23, and the sound waves 60 entering this space through the perforations 28 are partially absorbed and mixed together in this space to increase the overall sound absorbing efficiency of the construction. The membranes 27 are preferably provided with sufficient of the perforations 28 so that the area of the perforations constitutes about 8 to 15 per cent of the total area of the membranes. With this area of perforations, approximately 90% of the incident sound will pass through the perforations into the space 15 65 38 to be absorbed by the pad 23.

The modified form of ceiling construction shown in Fig. 4 is of the same general character as the construction shown in Figs. 1 to 3, except that a modified form of rail 40 is used. The body 41 of the runner or rail 40 is preferably triangular in cross section with a pair of outwardly extending upper flanges 42, which are adapted to be engaged by the clamps 15, as shown in Fig. 4. Spring clip 43 has a flat section 44, which may be spot welded to the upper surface of the membrane 27, and is provided with perforations 45 to register with the perforations in the membrane. The clip 43, which is adapted to permit the membrane 27 to be snapped up from below into engagement with the runner 40, extends upwardly 20 at approximately the same angle as the sides 46 of the triangular shaped rail 41, and has a shoulder 47 for engaging a side 46.

In the form of construction shown in Fig. 5, 35 transverse grillage channels 48 are secured below the main ceiling channels 49 by means of wires 50. U shaped wire clamps 51 have oppositely disposed clamps 52, which engage over the upper flanges 18 of a rail 12, similar to that used in the construction shown in Figs. 1 to 3. The legs of the wire clamp 51 may be secured together in clamping position by means of a wire 53 twisted about said legs. The membrane construction used in this form of ceiling is substantially the same as 40 that shown in Figs. 1 to 3.

In the modified form of construction shown in Fig. 6, a rail 54 may be composed of two channels 55 in back to back abutting position, the webs 56 of said channels being spot welded together to 45 form a rigid, unitary rail. Slots 57 are formed in the web 55 for receiving downwardly extending hooks 58 formed on each end of supporting rods 59. The rods 59 serve to accurately space apart the rails 54 and to also support the sound absorbing pad 23. The upper flanges 55 of the rail 54 may be provided with perforations 60 so that said flanges may be nailed directly to the ceiling in order to reduce the amount of space between the ceiling and membranes 60a supported by said rail. Inwardly extending, U shaped, gripping flanges 61 are formed along opposite upturned flanges 62, formed along opposite sides of the membrane 60a. The flanges 61 are arranged to embrace the lower flanges 63 of the rail 54. In installing the membranes 60a, they may be moved longitudinally of the rail 54 by a sliding action with the flanges 61 engaging the flanges 63, or the membranes 60a may be flexed slightly to slip the flanges 61 over the rail flanges 63. If desired, the type of membrane shown in Figs. 1 to 3 may be used on the construction shown in Fig. 6.

We would state in conclusion that while the illustrated examples constitute practical embodiments of our invention, we do not wish to limit 70 75 80 85 90 95 100 105 110 115 120 125 130 135 140 145 ourselves precisely to these details, since manifestly, the same may be considerably varied without departing from the spirit of the invention as defined in the appended claims.

5 Having thus described our invention, we claim as new and desire to secure by Letters Patent:—

1. In an acoustical ceiling construction, a plurality of supporting rails in spaced, parallel relation, perforated membranes positioned below said rails, said membranes having upturned flanges, the upper edges of said flanges abutting the bottom of said rails, resilient means for supporting said membranes on said rails with said flanges in firm contact with the bottom of said rails, and means above said membranes for absorbing sound. 10
2. In an acoustical ceiling construction, a ceiling, clamping members secured to said ceiling, supporting rails supported by said clamping members in spaced, parallel relation, connecting bars extending transversely between said clamping means, an acoustical absorbing pad supported by said bars, and perforated membranes supported by said rails. 15
3. In an acoustical ceiling construction, a plurality of supporting rails in spaced, parallel relation, outstanding flanges formed on the bottom of said rails, perforated membranes positioned below said flanges, spring clips secured to the upper face of said membranes and engaging the upper face of said flanges so as to support said membranes in closely abutting relation below said flanges, and sound absorbing means above said membranes. 20
4. In an acoustical building construction, a building surface, a plurality of supporting rails adjacent said surface, clamping members having oppositely disposed clamps engaging said rails so as to support said rails from said surface, locking means for preventing the disengagement of said clamps from said rails, perforated membranes supported by said rails, and acoustical sound absorbing material between said membranes and said surface. 25
5. In an acoustical ceiling construction, a plurality of rails in spaced, parallel relation, said rails having outwardly extending upper flanges, a ceiling, clamping means secured to said ceiling and having oppositely disposed clamps engaging said flanges, connecting bars having locking clamps for preventing the disengagement of said first mentioned clamps from said flanges, means on said clamping means for preventing the upward movement of said locking means, perforated membranes supported by said rails, and an acoustical pad supported above said membranes. 30
6. In an acoustical building construction, a building surface, a plurality of supporting rails secured to said surface in spaced, parallel relation, a plurality of perforated metal membranes positioned adjacent said supporting rails, spring clips welded to the inner face of said membranes, and adapted to secure said membranes to said rails, and means between said membranes and said surface for absorbing sound. 35
7. In an acoustical building construction, a plurality of elongated support members in spaced, parallel relation, a building surface supporting said support members, a plurality of perforated metallic membranes positioned adjacent said support members, attaching clips secured to each of said membranes intermediate the edges of said membranes so as to connect said membranes to said support members and sound absorbing material positioned between said membranes and said building surface. 40
8. An acoustical ceiling construction comprising a plurality of runners, perforated metal, membrane units below said runners, spring clips secured to said units and connecting the same to said runners, rod means spanning adjacent runners, and sound absorptive material carried by said rod means. 45
9. In a metallic membrane for ceiling construction, a planular body part, upstanding flanges on the sides of said body part, and separate spring clips associated with said membrane to resiliently clip the same to ceiling supports, said clips extending above said flanges and being adapted to retain the edges of said flanges against said ceiling supports. 50
